UNITED STATES PATENT OFFICE

2,258,729

DRAFT REGULATOR FOR HOT AIR FURNACES

Millard Whyte Best, Hamilton, Ontario, Canada

Application March 6, 1941, Serial No. 381,928

5 Claims. (Cl. 236—10)

My invention relates to improvements in draft control devices for hot air furnaces and the object of the invention is to provide a device actuated by the flow of air passing into or through the furnace to be heated whereby the passage of air past the check and draft dampers is synchronously controlled by the velocity of the air passing through the furnace to be heated.

A further and particular object of my invention is to provide a very sensitive device actuated by the air flow and which will immediately respond to any changes in the air velocity and in turn actuate the draft and check dampers.

Another object of my invention is to provide a very simple device which can be readily installed on any standard type or hot air furnace and which is also furnished with a simple adjustment whereby its responsive movement to air velocity changes can be readily altered.

With the foregoing and other objects in view as shall further appear, my invention consists of a draft control device formed and arranged all as hereinafter more particularly described and illustrated in the accompanying drawing, in which,

Figure 1 is a front elevational view of a hot air furnace furnished with my device.

Figure 2 is a side elevational view of the furnace as illustrated in Figure 1.

Figure 3 is an enlarged perspective view of my device as attached to the outer ends of the check draft inlet pipe and the furnace draft inlet pipe, the lower portion of the device being contained within the air inlet conduit through which air is entering the furnace to be heated, such conduit being shown broken away.

Figure 4 is a front elevational view of the upper portion of my device as attached to the check draft and furnace draft inlet pipes, and,

Figure 5 is a horizontal cross-sectional view through a fragmentary portion of the air inlet conduit and showing the lower portion of my device contained therein.

Like characters of reference indicate corresponding parts in the different views of the drawing.

In Figures 1 and 2 I show a standard hot air furnace, which comprises the usual central fire box 1 surrounded by a casing 2 to form a chamber surrounding the fire box wherein the air is heated to pass therefrom through the hot air pipes 3. The furnace flue pipe 4 extends from the dome of the fire box through the side of the furnace casing 2, all of which construction follows general standard practice.

The furnace is furnished with a grate draft pipe 5 which extends from the ash pit 6 of the grate outwardly through the casing 2. A check draft inlet pipe 7 extends upwardly and opens into the flue pipe 4. Air to be heated is directed into the air chamber in the furnace through a conduit 8 opening into the bottom of the casing 2. In the standard furnace the passage of air into the grate is manually controlled by a damper as is also the passage of air through the flue pipe. In my present invention I provide a device whereby the grate draft and check draft dampers are synchronously actuated to a degree proportionately to the velocity of air passing into the furnace chamber through the conduit 8.

As will be seen from the drawing, I provide an elbow at the bottom of the pipe 7 which has its open end extending in the same vertical plane as the open end of the pipe 5. The open ends of the pipes 5 and 7, which are positioned one above the other, carry a substantially 8 shaped member 9 which surrounds the ends of the two pipes and is suitably secured thereto. A second substantially 8 shaped member 10 is positioned to rest against the member 9. The lower rings of the members 9 and 10 are provided with a pair of lugs 11 having orifices therein and in which a bolt or pin 12 is contained. The opposite sides of the two lower rings are each furnished with a lug, the lower ring of the member 9 carrying a lug 13 and the lower ring of the member 10 carrying a lug 14. These lugs are so positioned upon their rings that they are normally spaced apart a slight distance.

A thumb-screw 15 is rotatably contained within the lug 14 and has its lower end threaded into an orifice in the lug 13. While the unthreaded upper end of the thumb-screw 15 is freely rotatable within the lug 14, it is retained against vertical sliding movement in the lug 14 by a cross-pin 16 so that as the thumb-screw is rotated the lug 13 is either drawn towards or moved away from the lug 14, depending upon the direction in which the thumb-screw 15 is turned. It will thus be seen that when the thumb-screw 15 is rotated that the 8 shaped member 10 will move or swing relatively to the 8 shaped member 9 about the bolt or pin 12 in the lugs 11, as shown in Figure 4.

The 8 shaped member 10 is formed at its lower end with a downwardly extending bracket 17 formed with a foot 18. The bracket 17 extends downwardly into the air conduit 8 and is positioned in close proximity to one of the side walls thereof and preferably extends downwardly to

the vicinity of the bottom of the conduit. The 8 shaped member 10 and its bracket 17 carry a spindle 19, the upper end of the spindle being pivoted in the upper end of the member 10 and the lower end of the spindle pivoted in the foot 18. In order to facilitate the insertion of the spindle 19, the central and lower portions of the member 10 are formed with channels 20 through which the spindle 19 extends. I form the ends of the spindle 19 with pivot points 21 which are contained within cups 22 threaded into the top of the member 10 and foot 18. In this manner a practically frictionless mounting for the spindle 19 is obtained.

The upper portion of the spindle 19 passing through the upper circular portion of the member 10 carries a damper disc 23 and the central portion of the spindle passing through the lower circular portion of the member 10 carries a damper disc 24, the damper 24 being positioned substantially at right angles to the damper 23. The lower portion of the spindle extending downwardly to the foot 18 carries a flap member 25 which is contained within the conduit 8. It is to be understood that the dampers 23 and 24 and the flap 25 are secured to the spindle 19 so that they move simultaneously.

The frame 10 and its contained spindle 19 are, at the time of installation, positioned at a slight inclination so that the flap 25 on the freely swingable spindle 19 will swing to a rest position across the air inlet conduit 8, as illustrated in full lines in Figure 5. When the flap 25 is in this position the damper disc 24 controlling the passage of air to the grate is swung fully open and the damper disc 23 in a position closing the entrance orifice to the pipe 7. As soon as the furnace has been lit, air will be drawn into the grate past the open damper 24 through the pipe 5, and in due course the air in the air chamber in the furnace will be heated to pass outwardly through the pipes 3, and fresh cold air will pass into the furnace through the conduit 8. As soon as the fresh air commences to pass along the conduit 8 into the furnace it impinges against the flap 25 and will swing such flap in a counter-clockwise direction, as illustrated in Figure 5.

The distance that the flap 25 will be swung will, of course, depend upon the velocity of the air passing through the conduit 8 and the velocity of the air will be proportionate to the heat of the furnace and the consequent rapidity with which the air in the furnace chamber is being heated to sufficient temperature to pass outwardly through the air pipes 3. As the flap 25 swings under the impingement of the air draft in the conduit 8, the dampers 23 and 24 will swing in unison therewith. The resultant opening movement of the damper 23 will permit a check draft to pass upwardly through the pipe 7 into the flue pipe 4 and the resultant closing of the damper 24 will reduce the volume of air passing into the grate of the furnace.

It will thus be appreciated that as the furnace becomes increasingly hot the velocity of air passing through the conduit 8 will increase which will cause the flap 25 to swing through a greater arc with the consequent enlargement of the check draft opening and closure of the grate draft opening, so that the speed of combustion in the furnace will be reduced. As the speed of combustion reduces and the heat in the furnace gradually decreases, the velocity of air passing through the conduit 8 will also decrease with the then proportionate gradual opening of the grate draft

damper and proportionate gradual closing of the check draft damper.

In this way the temperature and combustion in the furnace can be retained within close proximity to a predetermined degree, as when the furnace becomes too hot the check draft is gradually opened and the grate draft reduced or cut off, and when the furnace starts to cool down below a predetermined degree with the resultant reduction of air velocity in the conduit 8, the flap will gradually swing back with the resultant gradual closing of the check draft and opening of the grate draft.

In speaking of velocity of the air passing through the conduit 8, it is to be understood that no great velocity of air is required to swing the flap 25 but that the flap will readily swing under the natural slow moving air draft sucked through a hot air furnace.

If it is desired to increase or lessen the sensitivity or responsiveness of my device, the adjustment can be very simply achieved by manipulation of the thumb-screw 15. By rotating the thumb-screw 15 so that the lug 14 on the member 10 is moved upwardly and away from the lug 13 on the member 9, the member 10 and its leg 17, in swinging about the pin 12, will be increased in inclination from the vertical, as shown in Figure 4.

It will be understood that as the spindle 19 carrying the flap 25 increases in inclination with the member 10 and its leg 17, that the greater the inclination given to the spindle 19 the greater will be the effort or air velocity necessary to swing the flap from its position when at rest. Conversely the closer the spindle 19 is to being absolutely vertical, the less will be the effort or air velocity required to swing the flap. A very fine adjustment of my device can be secured through movement of the thumb-screw 15. While I have shown my spindle 19 carrying the dampers and the flap, as mounted in an 8 shaped frame which is movable in relation to another 8 shaped frame carried upon the ends of the air draft pipes, it is to be understood that I could mount my device in a number of other ways to secure the same result without departing from the spirit of my invention as set forth in the appended claims.

What I claim as my invention is:

1. In a hot air furnace, the combination with the draft and check dampers and the air heating chamber in the furnace having a cold air inlet, of a horizontally swingable member positioned within the path of the natural flow of air drawn into the furnace air heating chamber and gradually swinging under the impingement of an increasing air flow velocity to gradually move the draft damper towards a fully closed position and the check damper towards a fully open position.

2. A construction as claimed in claim 1, wherein in the draft and check dampers and the horizontal swingable member are secured upon a freely swingable slightly tilted vertical spindle.

3. In a hot air furnace, the combination with the draft and check dampers and the air heating chamber in the furnace having a cold air inlet, of a horizontally swingable flap carried on a slightly tilted vertical axis and positioned within the path of the natural flow of air drawn into the furnace air heating chamber and gradually swinging under the impingement of an increasing air flow velocity to gradually move the draft

damper towards a fully closed position and the check damper towards a fully open position.

4. In a hot air furnace, the combination with the draft and check dampers and the air heating chamber in the furnace having a cold air inlet, of a horizontally swingable flap carried on a slightly tilted vertical axis and positioned within the path of the natural flow of air drawn into the furnace air heating chamber and gradually swinging under the impingement of an increasing air flow velocity to gradually move the draft damper towards a fully closed position and the check damper towards a fully open position, a

member upon which the flap is swingably supported and means for altering the inclination of said member.

5. A construction as claimed in claim 4, where in the member supporting the flap is of substantially 8 shape and in the orifices of which the check and draft dampers are contained, a leg protruding downwardly from the 8 shaped member, a freely pivoted spindle extending from the top of the 8 shaped member to the bottom of the leg and upon which the dampers and the flap are secured.

MILLARD WHYTE BEST.
